UNITED STATES PATENT OFFICE

WILLIAM H. LEAVIN AND SAMUEL B. LEAVIN, OF NEW YORK, N. Y., ASSIGNORS, BY
MESNE ASSIGNMENTS, TO GOTHAM KNITBAC MACHINE CORPORATION, OF NEW
YORK, N. Y., A CORPORATION OF DELAWARE

KNITTING NEEDLE

Application filed July 17, 1928. Serial No. 293,430.

This invention relates to a knitting needle and particularly to devices of this nature adapted to be manipulated by hand, or in a machine of the class described in our application for Letters Patent, filed January 23, 1928, Serial No. 248,806, Patent No. 1,708,675, for the repair of runs in knitted fabrics.

One of the objects of the present invention is to provide a needle of the nature and for 10 the purpose referred to which may be rapidly and easily manipulated to reestablish the loops of the runs, without the exercise of any particular skill.

A further object of the invention is to provide a needle of the character and for the purpose referred to, which is simple in construction and so designed that it performs its function in an efficient manner.

Further objects of the invention will appear more fully hereinafter.

The invention consists substantially in the structure hereinafter described as illustrated in the accompanying drawing, and finally pointed out in the appended claims.

This application is a continuation in part 25 of our pending application Serial No. 248,807 filed January 23, 1928, for "Knitting needles". The subject matter of the present application relating to Figs. 1 to 5, inclusive, 30 is the same as appears in the above entitled case, while the matter relating to Fig. 6 is additional matter.

In the accompanying drawing,—

Figure 1 is an enlarged view in longitudinal section of a needle embodying our invention taken on the line 1—1 of Fig. 3, looking in the direction of the arrows, and showing the latch of the needle in open position.

Fig. 2 is a view in side elevation of the same showing the latch in closed position.

Fig. 3 is a front elevation of the same showing the latch in open position.

Fig. 4 is a view in transverse section taken 45 on the line 4—4, Fig. 1, looking in the direction of the arrows.

Fig. 5 is a diagrammatic view illustrating a run in the fabric to be repaired.

Fig. 6 is an enlarged longitudinal section 50 of a preferred form of needle embodying our

invention showing the latch of the needle in open position.

The needle embodying the present invention comprises generally a hook member and a latch member coacting therewith. The 55 hook member includes a shank 1. The shank, at its lower end, terminates in a hook portion, indicated at 2. Adjacent the juncture of the shank and the hook portion, the said shank is inclined at an angle to the rest of the shank as indicated at 3. The latch member 4 is pivotally connected at one end to the shank 1 in a slot 5 therein. Located in the slot 5 and secured to the shank in any suitable manner is a spring 7. The spring 7 is 60 positioned so as to engage the cam shaped portion 6 of the latch member and to normally hold said latch member under a slight tension in open position, as illustrated in Figs. 1 and 3.

If the needle is operated by hand, the shank 1 is secured to a suitable handle (not shown) so that it can be more readily operated. In case the needle is used in a run repairing machine, such as shown and described in our pending application for Letters Patent above referred to, the shank is 75 secured in the usual manner to the needle bar of the machine.

It is an important feature of our invention 80 that the parts of the needle above described should be of certain definite proportions and that they be disposed with respect to each other in certain definite relation. The latch member for instance should be of such a 85 length that, when it is closed its free end just engages upon the bill of the hook. In a needle constructed in accordance with our invention, for use in repairing runs in hosiery, for instance, the latch member is preferably an approximate length of .146 of an inch. The width of the hook portion is proportioned so that when the latch is closed thereon, the said latch member will lie at a predetermined angle with respect to the bill and shank of the hook. In order to have the latch member coact with the hook at the desired angle in closed position, it has been found that on a needle for repairing runs 95 for hosiery the hook portion should be ap- 100

proximately .043 of an inch in width. These proportions of the parts and their disposition with respect to each other will, of course, vary according to the nature of the particular fabric.

5 The needle is manipulated in repairing a run in knitted fabric whether by hand or in the machine referred to in the following manner.

10 The fabric containing the run, as illustrated in Fig. 5 is supported in a suitable manner in position to be operated on, so that the needle can be inserted between the cross threads *a* of the run. The cross threads forming the ladder of the run are, if desired, spaced apart sufficiently in any suitable manner to allow the needle to be inserted between them.

15 The hook 2 of the needle is then inserted into position to engage the first, cross thread of the run and said cross thread is then pulled upward into a loop. During this operation the latch is in open position, being held in such position by the spring 7. The needle is then thrust downwards again in front of the next succeeding cross thread *c* of the run. On this downward stroke of the needle the loop *b* slides up the shank of the needle, and over the latch, causing the latch to be swung back against the shank. The inclined portion 3 facilitates this operation. The needle is then withdrawn upwards from beneath the run in such a manner that the hook engages the second cross thread *c* of the run and 20 pulls the same upwards into a loop above the fabric. As the needle is ascending and pulling the second cross thread *c* upwards, previously formed loop *b* slides down the shank and forces the latch to close on the hook. 25 At the time the latch closes on the hook, the previously formed loop *b* slides off the needle and the loop formed in the second cross thread *c* is drawn through the previously formed loop *b*. This operation is continued 30 until the run has been completely mended. The last loop of the run may be secured in place in the stocking or other fabric in any convenient manner, as for instance by manually sewing it to the fabric.

35 In the construction shown in Fig. 6 we provide a needle for the purposes set forth which appears to be the most practical form by means of which repairs may be rapidly made in the fabric without skipping threads or otherwise producing an uneven repair. In this form of needle there is employed as before a straight shank portion 1 and an inclined shank portion 10. The inclined portion 10 lies at an angle with respect to the straight portion 1. In best practice this angle should be of the order of 20 to 30°. The inclined portion 10 then runs into a second inclined portion 3 which extends at an angle with respect to the portion 10, as in 40 the case of the form of needle shown in the

other figures. In other words, the needle of the form shown in Fig. 6 is the same in all respects as the needle shown in the other figures with the exception that the shank portion instead of being straight until it reaches the inclined portion 3 has another inclined portion of greater extent, as shown at 10. We have found in actual practice that a needle of this form is by far the most practical type yet devised by us and has the highly important feature in use that the needle when ascending does not tend to catch on the cross thread next following the thread being looped at the lever 4. With the type of needle shown in Figs. 1 to 3, inclusive, this sometimes occurs causing two of the cross threads to be caught by the hook during the looping operation. By providing the shank 1 with the inclined portion 10 the lever 4 is thrown back to the left, as will be apparent by comparing Figs. 1 and 6, so as to be less liable to catch on the next cross thread and foul the correct looping operation. Another highly important advantage of the form of needle shown in Fig. 6 is that as the needle ascends each time to catch a cross thread in the hook 2 it is found that the cross thread is directly in line with the hook and falls thereinto each time without skipping or missing a thread. This also results because of the inclined portion 10. The net result is that quick and better work is done with the form of needle shown in Fig. 6.

45 It will be understood that the spring 7 of the needles merely exerts sufficient tension on the latch to keep it in open position when manually raised or forced to that position by the action of the thread of the loops. When the latch is forced to its closed position the spring will not cause it to return to its open position when the loop which causes it to close slides off the hook and relieves the pressure on the latch. Such return of the latch to open position is accomplished by the next loop in the same manner as previously described.

50 What we claim as new and desire to secure by United States Letters Patent is:

1. A needle for repairing runs in knitted fabrics comprising a shank having a straight portion and a slotted inclined portion and a hooked portion joined to said slotted inclined portion by a second inclined portion, a latch member pivotally connected at one end in the slotted inclined portion and cooperating at its free end with the tip of the hooked portion, said second inclined portion being disposed at such an angle with respect to the slotted inclined portion and the hooked end portion that the width of the hook will permit the latch member to lie at a predetermined angle with respect to the tip of the hook and the inclined slotted portion of the shank when it is closed upon said tip.

55 2. A needle for repairing runs in knitted

fabrics having a shank comprising three portions each lying at an angle with respect to the other, one of said portions being slotted, and its adjacent portion being provided with a hooked shaped end and being disposed at such an angle with respect to its adjacent slotted portion that the tip of the hooked shaped end is a predetermined distance from the said adjacent slotted portion, and a latch member pivotally connected in the slot of said slotted portion and adapted to cooperate at its free end with the tip of the hooked shaped end.

3. A needle for repairing runs in knitted fabrics comprising a shank having a straight portion and a slotted inclined portion and a hooked portion joined to said slotted inclined portion by a second inclined portion, a latch member pivotally connected at one end in the slotted inclined portion and cooperating at its free end with the tip of the hooked portion, said second inclined portion being disposed at such an angle with respect to the slotted inclined portion and the hooked end portion that the width of the hook will permit the latch member to lie at a predetermined angle with respect to the tip of the hook and the inclined slotted portion of the shank when it is closed upon said tip and a tension spring disposed in the slotted inclined portion and arranged to exert a tension on the latch member to keep it in open position when it is raised by the action of a thread in the run being repaired.

35 In testimony whereof we have hereunto set our hands on this 16th day of July, A. D. 1928.

SAMUEL B. LEAVIN.
